UNITED STATES PATENT OFFICE.

EWALD M. SPIEKERMAN, OF LODI, CALIFORNIA.

PORTABLE IRRIGATING-HYDRANT.

1,263,814.

Specification of Letters Patent. Patented Apr. 23, 1918.

Application filed February 1, 1916. Serial No. 75,478.

To all whom it may concern:

Be it known that I, EWALD M. SPIEKERMAN, a citizen of the United States, residing at Lodi, in the county of San Joaquin, State 5 of California, have invented certain new and useful Improvements in Portable Irrigating-Hydrants; and I do declare the following to be a full, clear, and exact description of the same, reference being had to the 10 accompanying drawings, and to the characters of reference marked thereon, which form a part of this application.

This invention relates to improvements in hydrants used on irrigating pipe lines, the 15 object of the invention being to produce a simple and effective hydrant which may be transported from outlet to outlet of an irrigating pipe line and easily and quickly inserted and secured over the outlet prior to 20 the valve in the outlet being unopened and the said valve being thereafter engaged and opened for discharging into the hydrant. I am aware that hydrants have been used for 25 the same purpose but they usually have been complicated, heavy and expensive, and it is the aim of my present invention to provide a substitute which will not have these objectionable attributes.

A further object of the invention is to 30 produce a simple and inexpensive device and yet one which will be exceedingly effective for the purposes for which it is designed.

These objects I accomplish by means of 35 such structure and relative arrangement of parts as will fully appear by a perusal of the following specification and claim.

In the drawings similar characters of reference indicate corresponding parts in the several views.

40 Figure 1 is a side elevation of the complete hydrant.

Fig. 2 is a top plan view of the same.

Fig. 3 is a sectional view of the upper side of the hydrant showing the manner of 45 locking the cover in position thereon to prevent the overflow of water from the hydrant.

Fig. 4 is a sectional view of the hydrant as it appears when inserted over the pipe line outlet.

50 Fig. 5 is a side elevation of a modified form of hydrant from that shown in the other views.

Referring now more particularly to the characters of reference on the drawings my

improved hydrant comprises primarily a 55 cylindrical member 1, the inner surface of same flaring from one end to the other for a purpose as will presently appear. This member 1 is preferably made of any light endurable metal such as galvanized iron or 60 the like whereby it may be readily lifted and transported from place to place it being provided with handles 2 or other suitable engaging means for the purpose. Said body 1 has a discharge outlet 3 disposed at right 65 angles thereto. The upper end of the member 1 is provided with an outwardly flaring or tapered portion 1^a whereby the cap or cover 4 may be frictionally engaged therein to prevent the overflow of water, which 70 cover 4 may be further locked in position by means of a cross bar 5 pivoted to the said member 4 and adapted to engage overhanging hooks 6 secured to the portion 1^a whereby the cover 4 may be securely forced 75 into the tapered portion 1^a to prevent any possible overflow of the water from the hydrant.

In a great many instances this latter structure may not be needed and the said 80 body 1 may be made without a tapered end or cover, as shown in Fig. 5, in which the numeral 1^b designates the hydrant body having a discharge outlet 1^c.

The use of the hydrant is as follows, viz: 85

The body portion 1 is placed over the upper edge of the discharge outlet 7 of the irrigating pipe line 8 and is forced over the same. By reason of the flaring inner surface of the said member 1 this causes the member 90 to jamb or lock securely around the outlet 7 to prevent any undue escape of the water. The inner surface of the hydrant 1 is flared so as to be at an angle to the outer surface of the valved outlet so that there will be a 95 point of contact only around one edge of the member 7. This construction serves the double purpose of allowing the two to be wedged closely together and yet permits them to be more easily disassociated than 100 would be possible if the two surfaces paralleled each other and fit together telescopically. When the said hydrant is suitably wedged over the outlet 7 the valve 9 is then opened readily through the opened top of 105 the said member 1 and the water thereupon flows into the member 1 and out the outlet 3. An irrigating hose such as those com-

monly used for the purpose may be placed over the outlet 3 which is also tapered, as shown, and securely engaged thereto by means of a sliding ring 3^a mounted on the 5 said member 3. If the hydrant is desired for use with discharge outlets which are not suitably formed for receiving my improved hydrant in the wedged relation mentioned, then the user could readily form a ring of 10 cement or other material around the outlet and then fasten my improved hydrant over that with the same results.

As can readily be seen, by the use of my improved tapered hydrant, the same can be 15 readily and quickly frictionally engaged with the outlets, and when desired to transport the same from one outlet to the other, it is a very simple matter to disengage the same and take it from point to point.

20 In the now commonly used hydrant there are special fastening means which must be engaged or disengaged from the outlet which takes time and trouble and also those made in that manner are usually so heavy as 25 to render it more or less impracticable to transport them from one place to another.

From the foregoing description it can readily be seen that I have produced such a device as substantially fulfills the objects of the invention as set forth herein.

30 While this specification sets forth in detail the present and preferred construction of the device, still in practice such deviations from such detail may be resorted to as do not form a departure from the spirit of 35 the invention as defined by the appended claim.

Having thus described my invention what I claim as new and useful and desire to secure by Letters Patent is:

40 A portable hydrant for the valved outlet of an irrigation pipe comprising a cylindrical body, the inner sides of such body flaring out of parallel to the outer sides of the outlet whereby when the hydrant is fitted 45 over the outlet the top edge of the sides of the outlet will impinge and wedge against the inner sides of the hydrant to form a tight joint and at the same time to allow of the two to be easily disassociated at will.

50 In testimony whereof I affix my signature.
EWALD M. SPIEKERMAN.
